United States Patent Office

Des. 194,237
Patented Dec. 18, 1962

194,237

TARGET TOY

Norman M. Suydam, 3907 Detroit Ave., Toledo, Ohio

Filed Jan. 19, 1961, Ser. No. 63,623

Term of patent 14 years

(Cl. D34—5)

FIGURE 1 is a three-quarter front perspective view looking upwardly from the bottom end thereof, of a target toy, showing my new design;

FIGURE 2 is a three-quarter rear perspective view of the target shown in FIGURE 1;

FIGURE 3 is a three-quarter front perspective view looking downwardly on my new target design;

FIGURE 4 is a top plan view thereof; and

FIGURE 5 is a bottom plan view thereof.

The dominant feature of my design resides in the portions shown in full lines.

I claim:

The ornamental design for a target toy, as shown and described.
